TAPE-DISPENSING MECHANISM WITH
KNIFE-GUARDING MEANS

Alfred P. Krueger, Stratford, Conn., assignor to Derby Sealers, Incorporated, Derby, Conn., a corporation of Connecticut

Application March 11, 1949; Serial No. 80,841

13 Claims. (Cl. 164—84.5)

1.

This invention relates to tape-dispensing machines and, more particularly, to a device for dispensing pressure-sensitive tape, which is tacky or clingable upon one side.

At the present time there are many different kinds of pressure-sensitive tape, some of which are of such a character that they are readily severed or torn off against a tear-off blade, while others are relatively strong and tough and require the use of a sharp blade so that they may be severed easily and cleanly. As a matter of fact, in the devices of the present application a razor blade is employed as the tear-off element against which the tape is moved to be severed so that a very sharp severing edge is provided. It is always desirable to shield or guard the edge of the tear-off blade so that the fingers of the operator of the device will not come in contact with it, and this is particularly desirable where a very sharp blade is employed, or the user might receive a severe cut.

It is contemplated by the present invention to provide a guard or shield which will effectively guard the cutting edge of the tear-off blade, but which guard will be moved to an inoperative position when the tape is drawn toward the blade so as to expose the latter for contact with the tape. As tape of this character has a tendency to cling to the tear-off blade, it is desirable to provide a stripper to strip the tape from the blade so that there will be a free projecting end to be grasped by the fingers of the user. In the present device the guard for the tear-off blade is mounted upon one operated by the stripper member which is arranged to contact the non-tacky side of the tape, the parts being so constructed that when the tape is moved toward the tear-off blade for severance, the stripper member will be engaged by the non-tacky side of the tape and will also be moved. This movement of the stripper member will effect a retiring movement of the guard to expose the sharp edge of the tear-off blade and, after the tape has been severed, the stripper member will strip the leading end of the tape from the blade and move it to a position in which there will be a free projecting end to be grasped by the operator.

Specifically, in the present construction the guard or shield for the tear-off blade is mounted directly upon a part of the stripper member so as to be moved thereby and this guard is properly guided in its movements so that, while it will not actually contact the sharp edge of the blade and, therefore, will not dull the latter, it will move in front of the blade and prevent contact of the fingers of the user therewith.

2.

One object of the present invention is to provide an improved machine for dispensing pressure-sensitive tape.

A further object of the invention is to provide a machine for dispensing pressure-sensitive tape having a severing blade and a guard normally shielding said blade against contact by the hand of the user.

Still another object of the invention is to provide a new and improved machine for dispensing pressure-sensitive tape, which machine is provided with a fixed tear-off blade for the tape and a movable guard or shield for the blade, which member is carried by a stripping device to strip the tape from the severing blade.

Still another object of the invention is to provide a new and improved reel for holding a spool of tape in a tape-dispensing device.

To these and other ends the invention consists in the novel features and combinations of parts to be hereinafter described and claimed.

In the accompanying drawings:

Fig. 1 is a side elevational view of a tape-dispensing machine with the cover removed to show the interior mechanism;

Fig. 2 is a front elevational view of the device with the cover attached thereto;

Fig. 3 is a fragmentary view similar to Fig. 1 showing the parts in another position;

Fig. 4 is a top plan view of the device;

Fig. 5 is a detail perspective view of the stripper member and knife guard;

Fig. 6 is a perspective view of the reel for supporting the supply roll;

Fig. 7 is a fragmentary sectional view on line 35 7—7 of Fig. 4;

Fig. 8 is a view similar to Fig. 7 showing a slightly modified form of my device;

Fig. 9 is a view similar to Fig. 8 showing a further modification; and

Fig. 10 is a fragmentary sectional view on line 40 10—10 of Fig. 9.

To illustrate a preferred embodiment of my invention, I have shown a tape-dispensing device comprising a supporting base 10 from which rises a standard 11. A casting 12 is supported on the standard 11 by means of the threaded rod 13. This rod is threaded into a boss 14 of the casing 12, passes loosely through the standard 11 and receives on its projecting end a clamping nut 15 so that the case may be clamped in adjusted rotatable position relatively to the standard. The case 12 is open at one side and is provided with a removable cover 16 so that the roll of tape 17 may be inserted.

As shown more especially in Fig. 2, a second

rod or pin 17^a is threaded into the boss 14, and rotatably mounted on this pin is a reel for holding the supply roll of tape 17, this reel comprising in this instance a disk 18 and a hub 19. This reel may be held in place by a spring 20 disposed in a recess 21 in the hub 19, the spring being held under compression by the nut 22 threaded on the pin 17^a, and thus applying friction to the reel to resist rotation thereof and prevent backlash at the end of a dispensing operation.

The hub 19 is received in the opening in the spool 24 (Fig. 1) which holds the supply roll of tape, and is designed to fit snugly within this spool. However, the fit is sometimes sufficiently loose so that, as the tape is pulled from the roll and the latter rotated thereby, there will be some tendency for the supply roll of tape to turn relatively to the hub 19 and, in that event, the spool is apt to work off the hub, that is, to gradually move in a direction away from the disk 18 so that it may not be properly aligned with the mechanism of the dispenser. It will be noted, particularly from Figs. 3 and 6, that the hub or core 19 is knurled on its peripheral surface, as at 25, these knurlings being disposed spirally and given a lead in the proper direction so that if there is any rotation between the spool 24 and the core or hub 19, the spool will tend to move toward the disk 18. In other words, any rotation of the spool on the hub will cause the spool to "screw" onto the core instead of "screwing" off of the core. This maintains the supply spool against the disk 18 and, therefore, in proper alignment with the rest of the mechanism regardless of whether there is a loose or tight fit of the spool upon the hub.

The front wall of the case 12 is provided with an opening 27 through which the free end 28 of the tape is adapted to be pulled, and, adjacent the lower end of this opening, is mounted a roller 29 adapted to engage the tacky side of the tape so that a free end will protrude from the case to be grasped by the operator, as shown in Fig. 1.

Mounted adjacent the opening 27 and adapted to engage the non-tacky side of the tape is a stripper member comprising a plate 30 pivoted to the case at 31 and normally urged in a counter-clockwise direction, as shown in Fig. 1, by the spring 32. The movement of the stripper member may be limited by an arcuate slot 33 therein, which slot receives a pin 34 fixed to the case. Formed integrally with the plate-like member 30 and extending laterally at the upper edge thereof is a member 35 having at its forward ends depending ears 36 in which is rotatably mounted a stripping roller 37 adapted to engage the non-tacky side of the tape, the normal position of this roller when the parts are at rest being shown in Fig. 1.

Secured on the case at the upper edge of the opening 27 is a tear-off blade 39 having a sharp front edge 40 projecting over the opening 27 so as to be in position to contact the non-tacky side of the tape after it has been drawn from the roll. This blade may be held in position by a clamping plate 41, which clamping plate may, as shown in Fig. 4, be provided with forwardly projecting ears 42, one disposed at each side of the sharpened edge 40 of the blade 39, so as to shield the side edges of the blade. The edge of the blade, as will be noted, projects forwardly from the plate 41 between these ears so that the tape may be drawn over the sharp edge.

Hinged to the laterally projecting member 35 75

of the stripper at the rear end thereof is a guard member 44. This guard member is of plate-like form and is curved upwardly at its forward end as shown at 45 so that in its normal position of rest shown in Figs. 1 and 7, it projects upwardly and forwardly of the sharp edge of the blade between the ears 42, effectively shielding the blade against contact by the fingers. The hinge connection between this member and the member 35, as illustrated, comprises U-shaped projecting ears 46 at each side of the member 44, which ears embrace fingers 47 at the rear edge of the plate 35.

The intermediate portion of the guard member 44 is disposed between upper and lower pins 48 and 49, the pins being spaced to form between them a slot to receive the guard member and to act as guides for the guard member when it is moved from an operative to an inoperative or retracted position by movement of the stripper part 35. It will be seen from Fig. 1, for example, that the lower pin 49 supports the guard member in the position shown and if the same were not present the guard member would drop downwardly upon the part 35 of the stripper and expose the edge of the knife.

The normal or rest position of the parts of the device is shown in Figs. 1 and 7. It will be noted that the tape projects between the rollers 29 and 37 so that a free end is presented to be grasped by the operator. While the roller 37 may not be in contact with the upper or non-tacky surface of the tape it will preferably be sufficiently close to the roller 29 in this position so that when the tape is stripped from the severing blade, as will be hereinafter explained, it will be urged downwardly into contact with the roller 29 so that this free end will always be presented to the user.

In using the machine, the operator grasps the free end 28 of the tape and draws it from the roll. When a sufficient quantity of tape has been unwound, the tape is moved upwardly toward the severing edge 40. This movement, through contact of the roller 37 with the surface of the tape, effects movement of the stripper member from the position of Fig. 1 to that shown in Fig. 3. Due to the hinged connection of the guard 44 with the stripper member, the rear end of the guard member is likewise moved rearwardly and upwardly, thus causing the guard member to move from its operative position, shown in Fig. 1, to a retracted or inoperative position, shown in Fig. 3. It will be seen that in this position of the parts, as shown in Fig. 3, the tape may be drawn over the sharp edge 40 of the severing blade and severed.

Thereafter, the spring 32 will return the stripper member from the position shown in Fig. 3 to that shown in Fig. 1, and, likewise, the guard member will again be moved forwardly by the movement of the stripper. The movement of the guard member will be guided by the pins 48 and 49 so that it will be moved to a position in front of the sharp edge 40 of the severing blade. The stripping roller 37 will cause the tape to be stripped from the severing blade and moved downwardly into contact with the roller 29. It will be noted that the roller 37 contacts the tape at a substantial distance rearwardly of the line of severance so that a free end will project forwardly of the rollers 29 and 37.

In Fig. 8 of the drawing, I have shown a slightly modified form of the invention, wherein instead of the guide pins or studs 48 and 49, de-

scribed above, the guard member 44 is guided between upper and lower rollers 51 and 52, these rollers being rotatably mounted upon studs or pins 53 and 54 secured to the casing 12. In all other respects this form of my invention is like that previously described and illustrated in Figs. 1 to 7. The rollers 51 and 52 provide anti-friction guiding means for the guard member in its movements to and from operative position.

A further modification of my invention is shown in Figs. 9 and 10 wherein the guard member 44 is hinged to the stripper part 35 by means of a hinge pin 56 which passes through eyes 57 provided upon the guard member, and similar eye members 58 provided on the part 35. A coil spring 59 surrounds this spring pin, one end acting against the member 35 and the other against the guard member 44 so as to normally urge these members apart or urge the guard member upwardly as shown in Fig. 9.

An upper guide member 60 is provided and the spring 59 holds the guard member 44 in engagement with the lower surface of the member 60. This guide member can be provided in any desired form, but, as shown, it is provided by an integrally formed projection on the upper wall of the case 12. It will be apparent that as the spring 59 tends to urge the guard member 44 upwardly no lower guide member is necessary. It will be understood that the operation of the modified forms of the invention shown in Figs. 8 and 9 is like that of the form shown in Figs. 1 to 7.

While I have shown and described some preferred embodiments of my invention, it will be understood that it is not to be limited to all of the details shown, but is capable of modification and variation within the spirit of the invention and within the scope of the claims.

What I claim is:

1. A tape dispenser comprising a casing having an opening through which the tape is drawn, a severing blade supported by the casing adjacent the opening, a guard for the blade having a free end normally extending through the opening between the blade and the tape to cover the blade, actuating means for moving said guard inwardly and outwardly through said opening between the tape and the blade in an arcuate path, said means comprising an actuating member within the casing connected to said guard member and adapted to be engaged by the tape to be moved thereby as the latter is drawn toward the blade, and guide means engaging the guard at a point spaced from its connection with said actuating member to guide the guard in said arcuate path.

2. A tape dispenser comprising a casing having an opening through which the tape is drawn, means therein to support a roll of tape, a fixed severing blade carried by the casing against which the tape may be severed, a stripper member movably mounted in the casing to strip the tape remaining on the roll from the severing blade, a guard member carried by the stripper member and having a free end normally projecting through said opening to stand between the tape and the blade and forwardly of the edge of the blade, said stripper member having a part in contact with the tape as it issues from the roll, and means for guiding the free end of the guard member for movement between the knife and tape and to an unguarded position below the knife upon movement of the stripper member toward the blade.

3. A tape dispenser comprising a support for a roll of tape, a severing blade carried by the support against which the tape may be severed, a stripper member mounted on the support for movement toward and from the blade to strip the tape remaining on the roll from the severing blade, a guard member hinged to said stripper member to be moved thereby toward and from a guarding position with respect to the blade and normally standing forwardly of the edge of the blade and means for guiding the guard member in its movement.

4. A tape dispenser comprising a support for a roll of tape, a severing blade carried by the support against which the tape may be severed, a stripper member movably mounted on the support to strip the tape remaining on the roll from the severing blade, and a guard member carried by said stripper member and having a free end normally standing forwardly of the edge of the blade and between the blade and the tape path, said stripper member being engaged and moved by contact of the tape therewith as it is drawn toward the severing blade, said guard member being moved to inoperative position by movement of the stripper member toward the blade, and means for guiding the free end of the guard member for movement between the knife and tape and to an unguarded position below the knife upon movement of the stripper member.

5. A tape dispenser comprising a support for a roll of tape, a severing blade carried by the support against which the tape may be severed, a stripper member mounted on the support for movement toward and from the blade to strip the tape remaining on the roll from the severing blade, a guard member hinged to said stripper member and movable therewith to and from a guarding position with respect to the blade; said guard member normally standing forwardly of the edge of the severing blade; and means to guide the guard member in its movements.

6. A tape dispenser comprising a support for a roll of tape, a severing blade carried by the support against which the tape may be severed, a stripper member mounted on the support for movement toward and from the blade and having a part adapted to be engaged by the tape to effect movement of the stripper member; a guard member hinged to the stripper member; said guard member projecting forwardly over the edge of the blade and adapted to be moved by the stripper member to expose the edge of the blade; and means to guide the guard member in its movements.

7. A tape dispenser comprising a support for a roll of tape, a severing blade carried by the support against which the tape may be severed, a stripper member movably mounted on the support for movement toward and from the blade to strip the tape therefrom and having a part adapted to be engaged by the tape to effect movement of the stripper member, a guard member hinged to the stripper member, said guard member projecting forwardly over the edge of the blade and adapted to be moved by the stripper member to expose the edge of the blade, and means to guide the guard member in its movements, said means comprising spaced elements one upon each side of the guard.

8. A tape dispenser comprising a support for a roll of tape, a severing blade carried by the support against which the tape may be severed, a stripper member movably mounted on the support for movement toward and from the blade

and having a part adapted to be engaged by the tape to effect movement of the stripper member, a guard member hinged to the stripper member, said guard member projecting forwardly over the edge of the blade and adapted to be moved by the stripper member to expose the edge of the blade, and means to guide the guard member in its movements, said means comprising a roller upon each side of the guard member.

9. A tape dispenser comprising a support for a roll of tape, a severing blade carried by the support against which the tape may be severed, a stripper member movably mounted on the support for movement toward and from the blade and having a part adapted to be engaged by the tape to effect movement of the stripper member, a guard member hinged to the stripper member, said guard member projecting forwardly over the edge of the blade and adapted to be moved by the stripper member to expose the edge of the blade, means to guide the guard member in its movements comprising a guide element against which the guard member engages, and spring means urging said guard member against said element.

10. A tape dispenser comprising a support for a roll of tape, a severing blade carried by the support against which the tape may be severed, a stripper member movably mounted on the support for movement toward and from the blade and having a part adapted to be engaged by the tape to effect movement of the stripper member, a guard member hinged to the stripper member, said guard member projecting forwardly over the edge of the blade and adapted to be moved by the stripper member to expose the edge of the blade, means to guide the guard member in its movements comprising a guide element against which the guard member engages, and a spring acting between the stripper member and the guard member to hold the latter against said guide element.

11. A tape dispenser comprising a support for a roll of tape, a severing blade carried by the support against which the tape may be severed, a stripper member mounted on the support for movement toward and from the blade and having a part adapted to be engaged by the tape to effect movement of the stripper member, spring means to return said stripper member to normal position after the latter has been moved by engagement with the tape, a guard member hinged to the stripper member, said member projecting

forwardly over the edge of the blade and adapted to be moved by the stripper member to expose the edge of the blade and returned to a position forwardly of the blade to guard the same and means to guide said guard member in its movement.

12. A tape dispenser comprising a support for a roll of tape, a severing blade carried by the support against which the tape may be severed, a stripper member movably mounted on the support for movement toward and from the blade and having a part adapted to be engaged by the tape to effect movement of the stripper member, a guard member hinged to the stripper member, said guard member projecting forwardly over the edge of the blade and adapted to be moved by the stripper member to expose the edge of the blade, and means to guide the guard member in its movements, said means comprising spaced elements one upon each side of the guard and at least one of said elements being an anti-friction roller.

13. A tape dispenser comprising a support for a roll of tape, a severing blade against which the tape may be drawn to be severed, means for supporting said blade, a stripper member mounted adjacent said blade for movement toward and from the blade to strip the tape therefrom after a severing operation, a guard member carried by the stripper member and normally standing forwardly of the edge of the blade and being moved away from the blade by movement of the stripper member, said guard member being hinged to said stripper member and means to guide the guard member in its movement.

ALFRED P. KRUEGER.
